UNITED STATES PATENT OFFICE

110,804

DESIGN FOR A SUPPORTING BRACKET FOR A SHELF OR SIMILAR ARTICLE

Anita S. Dunn, Cedar Rapids, Iowa

Application September 10, 1937, Serial No. 71,545

Term of patent 3½ years

To all whom it may concern:

Be it known that I, Anita S. Dunn, a citizen of the United States, residing at Cedar Rapids, in the county of Linn and State of Iowa, have invented a new, original, and ornamental Design for a Supporting Bracket for a Shelf or Similar Article, of which the following is a specification, reference being had to the accompanying drawing, forming part thereof.

The figure is a view in perspective of a supporting bracket for a shelf or similar article, showing my new design.

I claim:

The ornamental design for a supporting bracket for a shelf or similar article, as shown.

ANITA S. DUNN.
